ANDREW J. MORSE, OF BOSTON, MASSACHUSETTS.

Design No. 3,959, dated April 5, 1870.

DESIGN FOR SODA-WATER FOUNTAINS.

The Schedule referred to in these Letters Patent and making part of the same.

To all whom it may concern:

Be it known that I, ANDREW J. MORSE, of Boston, in the county of Suffolk and State of Massachusetts, have invented or produced an Improved Design for a Soda-Fountain; and I do hereby declare that the following, taken in connection with the drawings which accompany and form part of this specification, is a description of my invention sufficient to enable those skilled in the art to practice it.

Apparatus for dispensing soda-water beverages, formerly made as simple fountains, are now-a-days for the most part elaborately constructed as ornamental cases, made of marble, each case inclosing the whole series of sirup-containing cans or bottles, each of which is connected to a sirup-cock or faucet, extending from the outside of the case, the soda-water pipe also extending through the case, and terminating in one or more draught-cocks at the side or sides of the case.

My invention has reference to a peculiar shape or design for such a soda-water and sirup apparatus or fountain case.

This design is shown in the accompanying photographic representation.

A rectangular box, *a*, is made of the necessary capacity for holding the desired number of sirup-cans, which is arranged in a single row between the opposite ends, or from end to end, with outlet orifices connected with the respective sirup-faucets *b*, or is arranged in two rows, if desirable, with a double series of sirup-faucets, (on the opposite sides of the case,) one series for each set of cans.

Over the sirup-cocks or faucets are seen the draught-cocks *c*, for drawing the aerated or gas-impregnated

water, these cocks projecting from the same wall *d*, to which the sirup-cocks are fixed.

The case is surmounted by a peculiar roof, the opposite and similar sides of which slope toward the front and back of the case, this roof being formed double or two-storied, the upper part being composed of two stationary roof-pieces, *e f*, and the lower part of two pieces, *g h*, each or one of which is hinged and serves as a lid, through the opening covered by which, the cans are introduced, removed, and filled.

Each roof-piece, *e f g h*, projects at its ends and eaves beyond the walls of the case, as seen in the photograph.

The hinges *i* are screwed at one end of each to the lid *g* (or *h*) and at the other end to an adjacent vertical piece, *k*, placed between the lid and the stationary roof-piece above it.

Each end wall is continued up between the two roofs, as seen at *l*, and the outer surface of all or of either of the walls may be ornamented by figures cut in relief or intaglio, or by metal ornaments secured upon them.

It is the peculiarly-constructed roof surmounting the case, or in the case so surmounted, that constitutes my improved design for a fountain or case for dispensing soda-water beverages.

I claim, as a new design for a fountain for soda-water beverages, a marble case, surmounted by the peculiarly-formed roof, as shown and described.

ANDREW J. MORSE.
